(57) **CLAIM**

The ornamental design for an alternator mounting bracket, as shown and described.

DESCRIPTION

FIG. 1 is a front perspective view of the alternator mounting bracket showing the design in an environment of use; FIG. 2 is a rear perspective view of the alternator mounting bracket showing the design in the environment of use; FIG. 3 is a front plan view of the alternator mounting bracket of FIG. 1;

FIG. 4 is a left side elevation view of the alternator mounting bracket of FIG. 1;

FIG. 5 is a right side elevation view of the alternator mounting bracket of FIG. 1;

FIG. 6 is a top plan view of the alternator mounting bracket of FIG. 1;

FIG. 7 is a bottom plan view of the alternator mounting bracket of FIG. 1; and,

FIG. 8 is a rear elevation view of the alternator mounting bracket of FIG. 1.

The broken lines in the drawings are for the purpose of illustrating portions of the alternator mounting bracket that form no part of the claimed design.
